CLAIM

The ornamental design for an electric fryer, as shown and described.

DESCRIPTION

FIG. 1 is a front elevational view of an electric fryer showing my new design;

FIG. 2 is a rear elevational view thereof;

FIG. 3 is a top plan view thereof;

FIG. 4 is a bottom plan view thereof;

FIG. 5 is a left side elevational view thereof, wherein the right side elevational view is a mirror image of the left side elevational view; and,

FIG. 6 is a top, left perspective view thereof.
